(57) **CLAIM**

The ornamental design for a puzzle table as shown and described.

DESCRIPTION

FIG. 1 is a front, right and top perspective view of a puzzle table showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of detail 9 in FIG. 2; and,

FIG. 10 is an enlarged view of detail 10 in FIG. 2.

The long dash-short dash broken lines annotate the enlarged detail views and form no part of the claim.
